J. A. COOK.
STREET TRAFFIC SIGNAL.
APPLICATION FILED SEPT. 21, 1920.

1,375,280.

Patented Apr. 19, 1921.

Atty's.

UNITED STATES PATENT OFFICE.

JAMES A. COOK, OF EAST BRIDGEWATER, MASSACHUSETTS.

STREET-TRAFFIC SIGNAL.

1,375,280.

Specification of Letters Patent. Patented Apr. 19, 1921.

Application filed September 21, 1920. Serial No. 411,698.

To all whom it may concern:

Be it known that I, JAMES A. COOK, a citizen of the United States, residing at East Bridgewater, in the county of Plymouth and 5 State of Massachusetts, have invented new and useful Improvements in Street-Traffic Signals, of which the following is a specification.

This invention relates chiefly to a signal 10 for directing street traffic, including a box having an opening, an electric lamp or other illuminator, behind said opening, arranged to project light rays through the opening, and a sign filling said opening, and visible 15 either by reflected light (daylight) or by transmitted light from the illuminator.

A sign which is suitably stiff and rigid and is not affected by rain and snow, includes 20 a pane of clear glass, and means preventing the passage of artificial light through portions of the pane, and exposing other portion for the passage of light rays, the exposed 25 portions having the form of sign characters.

One object of the invention is to provide 30 a sign for the above-mentioned use, the essential portions of which are a single pane of clear glass, and two coatings of paint spread upon and adherent to the glass, the nature of 35 said coatings being such that sign characters are formed on the pane, which are rendered legible by daylight reflected from one side of the pane, and by artificial light transmitted through the portions of the pane from the opposite side thereof, said pane and 40 coatings constituting an effective sign of minimum cost.

Another object is to enable a bull's eye to be conveniently associated with the sign.

The invention is embodied in the improvements hereinafter described and claimed.

Of the accompanying drawings forming a part of this specification,—

Figure 1 is a front side view of a portion of a signal embodying the invention, parts 45 of the box being broken away.

Fig. 2 is a section on line 2—2 of Fig. 1.

Fig. 3 is a side view of the sign looking toward its inner side, showing the sign partially completed.

Fig. 4 is a view similar to Fig. 3, showing the sign completed.

Fig. 5 is a magnified fragmentary section on line 5—5 of Fig. 3.

Fig. 6 is a magnified fragmentary section 55 on line 6—6 of Fig. 4.

Fig. 7 is a fragmentary perspective view.

The same reference characters indicate the same parts in all of the figures.

In Figs. 1 and 2 of the drawings, I show a portion of a box 12, mounted on a pedestal 60 13, and containing an illuminator 14, of any suitable kind, here shown as an incandescent electric lamp.

In each side of the box is an opening 15, containing the sign hereinafter described. 65 Said sign is formed as a filler for said opening and includes a pane 16 of clear glass, and two surface coatings 17 and 18, painted upon the pane and contrasting strongly in color with each other, the material of said 70 coatings being mixed paints adapted to be applied by a brush.

The coating 17 is opaque and light absorbing, the color of said coating being preferably black. The continuity of the 75 coating 17 is interrupted by sign-forming openings 19, exposing portions of the pane.

The coating 18 is translucent and light reflecting, and is preferably composed of any suitable white paint. The coating 18 80 covers the exposed portions of the pane, so that the sign characters are rendered legible by daylight reflected from one side of the pane, and by artificial light transmitted from the opposite side of the pane, through 85 the translucent coating 18 and the openings in the opaque coating 17.

The thickness, composition, and color of the coatings 18 are such that the portions which cover the openings 19 reflect daylight 90 at the outer side of the pane, so that the sign characters stand out in strong contrast to the opaque coating 17, and are sufficiently legible by daylight for all practical purposes.

The portions of the coating adhering to the portions of the pane which are exposed at the sign openings 19, so diffuse artificial light from the illuminator 14, that the sign characters appearing at the front 100 of the pane present a uniform tint or color, the incandescent filament of the illuminator 14 being rendered invisible by the coating 18.

It will now be seen that my improved sign may be produced by the simple operation of applying two coatings of paint to a single pane of glass, said coatings adhering closely to the glass and preventing access of moisture to the portions of the glass forming the sign characters. The coatings are in effect 105 inseparable from the glass, so that the sign may be handled, applied and removed as a

- single part. The cost of manufacture is considerably less than that of a sign which necessarily includes a plurality of glass panes and character forming means interposed between the panes.
- 5 To render the sign more conspicuous, particularly at night, I provide a light-transmitting bull's-eye 20, preferably of red glass, contrasting in color with the sign characters.
- 10 The bull's-eye 20 is secured in any suitable way at the front side of the pane 16, as by an annular sheet metal frame 21 embracing the margin of the bull's-eye and provided with ears 22, and elongated strips 23 secured
- 15 to said ears at 24 and extending across the outer side of the pane, the ends of the strips being attached, as by rivets 26 to the box 12 at opposite ends of the opening 15. To permit the unobstructed transmission of artificial light through the bull's-eye, I interrupt the coatings 17 and 18 to provide a supplemental opening 25, so formed and arranged that it exposes or leaves uncoated the portion of the pane with which the
- 20 bull's-eye contacts, so that light from the illuminator 14 is not absorbed to any noticeable extent by the pane and passes undifused through the pane and through the bull's-eye.
- 25 The bull's-eye is attached to the box independently of the pane 16, so that in case of breakage of the pane a new pane may be substituted without removing the bull's-eye from the box.
- 30 As shown by Fig. 1 I form and arrange the securing means to avoid interference of the same with the sign-forming openings.
- 35 The portion of the box 12 bounding the opening 15 and supporting the pane 16 and the strips 23 is a frame portion 12^a, displaceably connected as by hinges 28 with the fixed body portion of the box, said frame portion and the pane constituting a door which may be swung outward from the box
- 40 to facilitate the removal of a broken pane and the substitution of a new one therefor without disturbing or removing the bull's-eye. The opaque coating 17 prevents the transmission of light through the portions of
- 45 the pane adjacent to the bull's-eye, so that the latter, when illuminated, stands out in strong contrast to the adjacent portions of the pane.
- 50 The pane is detachably secured to the inner side of the frame portions 12^a by suitable means, such as displaceable cleats 27, engaged with said frame portion and located within the box and detachably securing the pane in its operative position.
- 55 The coatings 17 and 18 constitute an opaque screen located at one side of the pane

and provided with the said sign forming openings 19 and supplemental opening 25.

It will be seen that the box and the pane 16 collectively constitute a casing, a portion 65 of the external surface of which is formed by the outer side of the pane, so that the sign characters are rendered legible by daylight reflected from the translucent coating 18 through the pane, and from the outer side 70 of the latter, and by artificial light from the illuminator within said casing. A simple and effective signal casing, adapted for both day and night use, is therefore provided by assembling two essential elements, viz., a 75 box having an opening, and a transparent pane, the outer side of which forms a part of the external surface of the casing, said pane having, as an inseparable part thereof, the coatings 17 and 18.

80 I claim:

1. A signal, adapted for both day and night use, said signal comprising a box having an opening, a transparent pane secured in and filling the area of said opening, the 85 box and pane constituting a casing, a portion of the external surface of which is formed by the outer side of the pane, an illuminator inclosed by said casing, two surface coatings of material adherent to the 90 pane, painted on the inner side of the pane, and contrasting strongly in color with each other, one coating being opaque, light-absorbing, and interrupted by sign-forming openings exposing inner side portions of the 95 pane, and the other coating being translucent and light-reflecting, and covering the said exposed inner side portions, so that the sign characters are rendered legible, by daylight reflected from said translucent coating through the pane, and from the outer side of the latter, and by artificial light from said illuminator.

100 2. A signal substantially as specified by claim 1, each of said coatings being interrupted to form a supplemental opening, exposing another inner side portion of the pane, and permitting the unobstructed transmission of artificial light through both coatings, and through the pane, the signal comprising also a light-transmitting bull's-eye colored to contrast with the translucent coating, covering said supplemental opening, and secured at the front side of the pane, said supplemental opening permitting rays of 115 light to pass unobstructedly through the pane and bull's-eye, the screen preventing the passage of light rays through portions of the pane adjacent to the bull's-eye.

110 120 In testimony whereof I have affixed my signature.

JAMES A. COOK.
